UNITED STATES PATENT OFFICE.

GRANT TEMPLE, OF CLEVELAND, OHIO.

ROTARY ENGINE.

1,218,716.

Specification of Letters Patent. Patented Mar. 13, 1917.

Application filed March 18, 1915. Serial No. 15,209.

To all whom it may concern:

Be it known that I, GRANT TEMPLE, a citizen of the United States, residing at Cleveland, in the county of Cuyahoga and State of Ohio, have invented a certain new and useful Improvement in Rotary Engines, of which the following is a full, clear, and exact description, reference being had to the accompanying drawings.

10 This invention relates to rotary engines adapted to be driven by pressure fluid, and has for its general object the provision of a simple, efficient engine. My engine comprises an annular cylinder and a rotary piston, and another object is to provide an efficient means for intermittently closing one point of the passage for the piston so arranged as to be thoroughly steam tight and not rendered inefficient by wear. Another object is to provide a simple and efficient means for operating this closing member. My invention is hereinafter more fully described in connection with the drawings and other features and objects will become apparent in the description and the essential characteristics are set forth in the claims.

Referring to the drawings, Figure 1 is a side elevation of my engine; Fig. 2 is a vertical section through the central plane of the cylinder; Fig. 3 is a horizontal section taken substantially through the axis about which the piston rotates; Fig. 4 is a sectional side elevation opposite the side shown in Fig. 1; Fig. 5 is a detail, being a side elevation of the piston; Fig. 6 is an end elevation of the same; Fig. 7 is a transverse section through one of the piston rings, in an enlarged scale; Fig. 8 is a diagrammatic view showing a compound arrangement of my engine.

40 Referring to the drawings by reference numerals, 10 and 11 are cylinder members having registering annular grooves forming the annular cylinder bore 12 for the piston 14. These members 10 and 11 are shown as having abutting radial flanges 15, through which extend a series of bolts 16, for holding these members together. A suitable base 18 is preferably made integral with the member 11 and is shown as extending substantially laterally equal distances from beneath both the members 10 and 11, so that the weight of the engine will be properly balanced thereon. The piston 14 is rigidly connected with a thin circular disk 20, which is rigidly connected at its center by hubs 21, with the driving shaft 22, running in bear-

ings 23 and 24, shown as carried on brackets integral with the members 10 and 11. This shaft extends through stuffing boxes 26, at the center of the members 10 and 11, the adjacent portions of which are recessed to receive the hub members 21 of the disk 20. From these recessed portions the members 10 and 11 extend in radial planes, slightly spaced from the disk 20 to the semi-circular grooves forming the cylinder bore of the piston. Suitable radial ribs 27 may be provided to strengthen these members.

Adjacent the periphery of the circular portions 10 and 11, is a short cylindrical drum-like member 30, rotatable in registering cylindrical recesses, formed in cylinder members 32 and 33, shown as integral with the members 10 and 11 respectively. The drum is preferably carried on a transverse shaft 34, having its axis parallel with the shaft 22 and adapted to be driven in synchronism therewith by twin spur gears 35 and 36, rigid on the shafts 22 and 34, respectively. This drum-like member forms the gate for closing the piston passage, and its periphery is adapted to contact with the periphery of the disk 20, and the sides of the drum extend outwardly past the cylinder bore, as shown in Fig. 3, thereby preventing steam in the cylinder bore passing the gate. A portion of the drum is cut away, as shown at 37, providing a recess of such shape and size as to allow the piston to pass the gate as the gate and disk are rotated together. While the recess is passing the disk, this gate member of course does not close the cylinder bore, and it is obviously desirable to have the recess portion 37 occupy as little of the circumference of the drum as possible. The remaining portion of the circumference must contact tightly with the edge of the piston disk to prevent passage of steam while the piston is being driven. As a means for providing such a contact irrespective of the relative expansion of the metals, the wear, etc., I have shown a spring member 38, substantially like a piston ring and extending around the gate from points immediately adjacent each side of the recess 37, and having its surface adapted to spring against the edge of the disk and having its sides snugly engaging a groove in the cylinder 30.

It is necessary to provide a steam tight joint between the periphery of the piston disk and the members 10 and 11, and still

allow the disk to rotate freely. This I prefer to accomplish by means of rings 40, carried by the members 10 and 11 and closely fitting the disk at its periphery and 5 preferably composed of a soft lubricating metal such as babbitt for example. To prevent the leakage of steam outwardly between the flanges 15 and 16, I have provided a strip of packing 42, lying in registering grooves in the members 10 and 11 and 10 extending entirely around the cylinder bore and around the drum 30, inside of the bolts 16.

Inlet and exhaust ports 44 and 45 respectively, are positioned at either side of the gate and spaced apart a distance corresponding to the movement of the piston through the interval during which the recess is passing the adjacent point on the 20 periphery of the piston disk. The steam inlet may be controlled by any suitable valve mechanism. For example, I have shown a valve casing 46, to which the steam pipe 47 leads and having therein a piston 48, operated by a piston rod 49 to cover and uncover a port 50 communicating with the port 44. The rod 49 is shown as extending toward the shaft and connected with a strap 52, engaging a slot in an eccentric 53, rigid on 25 that shaft, these parts being arranged to open the inlet valve quickly and maintain it in the open position while the piston 14 is passing from the inlet port 44 around to the right as far as desired, (Fig. 2) prefer- 30 ably until it approaches the exhaust port 45, when the steam is shut off and the steam in the cylinder exhausts through the port 45 and a suitable exhaust pipe indicated at 54. The rotation of the piston disk and gate 35 continues between the ports 45 and 44 by momentum, there being provided a suitable fly wheel 56 on the shaft 22.

The surface of the piston 14, fitting the bore, is necessarily arcuate and its ends 57 45 and 58 preferably lie in radial planes. The piston may be secured to the disk by bolts 59 extending through outwardly projecting ears 60, integral with the disk 20 and fitting into recesses in the ends of the piston. The 50 piston is shown as cut away to provide recesses 61 for the head and nut of the bolt, allowing them to clear the bore of the cylinder. Piston rings 63 may be provided having their free ends held in the groove by 55 means of the heads of screws 65, engaging shoulders in suitable slots 66, allowing expanding movement of the piston rings while the heads of the screws stand beneath the surface of the piston to clear the cylinder 60 bore. In order that the rings may pass the gate member and again engage the cylinder bore without their forward edges engaging the edges where the bore for the gate meets the cylinder bore, I have shown the rings 65 as being tapered forwardly, that is with the

forward side 67 of a smaller diameter than the rear side, which engages the cylinder bore. As the piston rings move entirely in one direction it will be seen that this construction obviates the difficulty mentioned 70 without detracting from the efficiency of the rings. I prefer to chamfer the rear edge 68 of the piston rings so that steam pressure behind the ring will tend to spread the same into a close engagement with the cylinder. 75

As the bearings for the shaft 34 become worn, the steam pressure on one side of the gate drum will cause excessive friction between the opposite side of the drum and its 80 casing. Accordingly, I fit into the openings in the casing through which the shaft 34 extends, floating stuffing boxes 71 embracing the shaft 34 which is carried in bearing members 70, one portion of each of which 85 is rigid with the block 73 having threaded engagement with a screw 74, having right and left hand threads, one end engaging the blocks 73 and the other threaded blocks 72 abutting a boss 75 rigid with the side 90 members 10 and 11. The screw may be rotated by an integral collar 76, shown as having holes for a spanner wrench, and lock nuts 77 may be provided at each side of the collar 76. These screws are arranged 95 to move the bearings toward a point where the live steam pressure comes onto the cylindrical gate so that the thrust of this steam may be received entirely on the bearings for the shaft 34, allowing the surface 100 of the drum to rotate freely in its casing.

Fig. 8 diagrammatically illustrates a compound arrangement for my engine, in which a main shaft 80 carries a series of disks 20, each driven by its piston 14 in the annular cylinders in the casing, which are indicated in dotted lines at A, B, C, and D. The steam at boiler pressure is led to the casing A through a pipe 82 and exhausts at a lower pressure through a pipe 83, leading to the 110 casing B, entering on the opposite side of the drive shaft from the inlet port of the casing A. This unit exhausts in turn through a pipe 84, taking steam at a lower pressure which drives the piston in the casing C and exhausts through a pipe 85, to the unit D, from which it exhausts at a low pressure through an exhaust pipe 86. Suitable valves may control the connecting pipes of these units and each successive piston is preferably relatively larger than the piston of the unit from which it receives steam and may be carried on a larger disk, so that the application of power may be balanced as the steam pressure reduces in passing from one 115 unit to the other.

Having thus described my invention, what I claim is:

1. In a rotary engine, the combination of a cylinder having an annular bore, a piston 130

- revolute in said bore, a circular disk connected with the piston and a driving shaft rigidly carrying the disk, a revolute member adapted to extend into and close the bore 5 and having a recess for admitting the piston and allowing it to pass the revolute member, bearings for said revolute member, means for admitting steam to said cylinder at one side of the revolute member, and 10 screw members carrying the bearings for adjusting the bearings to move the revolute member toward the side receiving the steam pressure.
2. In a rotary engine, the combination of a cylinder having an annular bore, a piston fitting in and revolute in said bore, a circular disk connected with said piston at its periphery, a shaft rigidly carrying said disk, means for intermittently closing said bore, 15 means for admitting steam to and exhausting it from the cylinder, and packing rings of a lubricative nature carried by the cylinder member and tightly engaging the sides of the disk adjacent its periphery, the edges 20 of said rings conforming to the bore of the cylinder.
3. In a rotary engine, the combination of a cylinder having an annular bore, a gate adapted to be projected across a portion of 25 said bore and means for operating it to intermittently close the bore, a piston revolute in said bore, and rings on said piston having their forward edges of smaller diameter than the rear edges.
4. In a rotary engine, the combination of a cylinder having an annular bore, a gate adapted to be projected across a portion of 30 said bore and means for operating it to intermittently close the bore, a piston revolute in said bore, and rings on said piston having their forward edges of smaller diameter than the rear edges.
5. In a rotary engine, the combination of a cylinder having an annular bore, a gate adapted to be projected across a portion of 35 said bore and means for operating it to intermittently close the bore, a piston revolute in said bore, the piston rings having their forward edges of smaller diameter than the rear edges, slots adjacent the split in the ring, and means engaging said slots below the surface of the rings to prevent the ends 40 springing outwardly when passing the gate.
6. In a rotary engine, the combination of a cylinder having an annular bore, a gate adapted to be projected across a portion of 45 said bore, means for operating it to intermittently close the bore, a piston revolute in said bore, and piston rings having their forward edges of smaller diameter than the rear edges and having their rear edges chamfered inwardly so that steam pressure 50 behind the ring tends to expand the same.
7. In a rotary engine, the combination of a cylinder having an annular bore, a piston revolute in said cylinder, a rotatable member adapted to extend into and close the bore 55 and having a recess for admitting the piston and allowing it to pass such member, axial bearings for the revolute member, adjustable screws carrying these bearings and adapted to move them in a direction diagonally toward that portion of the rotatable member which receives the incoming steam pressure, and means for admitting steam to the cylinder at one side of the rotatable member.
8. In a rotary engine, the combination of a cylinder having an annular bore, a piston revolute in said bore, a driving shaft and means connecting the piston therewith, a rotatable valve extending into said bore adapted to intermittently close the same and 60 allow the piston to pass, a casing for the valve, a shaft therefor extending through the casing and bearing members each side of the valve outside of the casing, oppositely threaded screws carrying said bearing members and adapted to be rotated to adjust the valve, the axes of the screws lying substantially in a plane extending diagonally through the valve and the opening in the cylinder which the valve closes at the side receiving 65 the live steam pressure, and means for admitting steam to the cylinder at one side of the valve.
9. The combination, with a cylinder, of a piston circular in cross section, and a ring 70 for the piston split at one point and having its edge beveled inwardly so that steam pressure engaging such beveled edge may tend to expand the ring into engagement with the cylinder.
10. The combination of a cylinder having an annular bore, a piston curved longitudinally and adapted to closely fit said bore and revolve in the same, a shaft, a disk rigid on the shaft extending outwardly to the bore, separated projections on the disk extending into the bore, corresponding slots in the piston receiving said projections, screws extending through 75 portions of the piston and through said projections, a plurality of piston rings extending transversely around the piston between said projections, means for intermittently projecting across said bore and thus closing the same, at one point, and means for loosely holding the ends of the piston rings from 80 springing outwardly.
- In testimony whereof, I hereunto affix my signature in the presence of two witnesses.
